US0D1041882S

(12) United States Design Patent (10) Patent No.: US D1,041,882 S
(45) Date of Patent: * Sep. 17, 2024

(54) HANDBAG

(71) Applicant: Bottega Veneta S.R.L., Montebello Vicentino (IT)

(72) Inventor: Matthieu Blazy, Milan (IT)

(73) Assignee: Bottega Veneta S.R.L., Montebello Vicentino (IT)

() Term: 15 Years

(21) Appl. No.: 29/900,525

(22) Filed: Aug. 22, 2023

(30) Foreign Application Priority Data

Feb. 24, 2023 (EM) 015012557-0010

(51) LOC (14) Cl. 03-01

(52) U.S. Cl.

USPC D3/232
